US0D1043376S

(12) **United States Design Patent** (10) **Patent No.:** **US D1,043,376 S**
(45) **Date of Patent:** **** Sep. 24, 2024**

(54) **WATCH**

(71) Applicant: **RICHEMONT INTERNATIONAL SA**, Villars-sur-Glane (CH)

(72) Inventor: **Constanza Candamil**, Geneva (CH)

(73) Assignee: **RICHEMONT INTERNATIONAL SA**, Villars-sur-Glane (CH)

(**) Term: **15 Years**

(21) Appl. No.: **29/837,585**

(22) Filed: **May 6, 2022**

(30) **Foreign Application Priority Data**

Mar. 22, 2022 (WO) WIPO114934

(51) **LOC (14) Cl.** **10-02**
(52) **U.S. Cl.**
